UNITED STATES PATENT OFFICE.

JOHN F. MORGAL, OF DAYTON, OHIO.

CUTTER.

1,184,368.

Specification of Letters Patent. Patented May 23, 1916.

Application filed January 10, 1914, Serial No. 811,326. Renewed September 23, 1915. Serial No. 52,305.

To all whom it may concern:

Be it known that I, JOHN F. MORGAL, a citizen of the United States, residing at Dayton, in the county of Montgomery and State of Ohio, have invented certain new and useful Improvements in Cutters, of which the following is a specification, reference being had thereto to the accompanying drawings.

10 This invention relates to cutters having removable blades.

The object of the invention is to provide means whereby the blade of a cutter may be secured in position in such a manner that it will be held firmly against displacement and will resist any normal strain to which it may be subjected; and further, to so construct the fastening means that they can be quickly and easily manipulated to fasten the blade in position or to release the same; that they will comprise a minimum number of parts, thus materially reducing the cost of manufacture; and that the blade may be placed in position independently of the fastening member.

25 In the accompanying drawings, Figure 1 is a side elevation, partly broken away, of a rotary cutter embodying my invention; Fig. 2 is an edge view of such a cutter, partly in section; and Fig. 3 is a detail view of one of the cutter blades.

30 In these drawings I have illustrated my invention as applied to a rotary cutter for a milling machine but it will be understood that this type of cutter is chosen for the purpose of illustration only and that the invention can be applied to cutters of various kinds without departing from the essential features thereof. The body portion or 35 cutter head, which is shown at 1, is provided with blade-receiving seats which, in the present embodiment of the invention, comprise transverse slots 2 into which the blades fit. In cutters of this type, and particularly in milling cutters, the work must be done with great exactness and any material variation will render the piece operated upon worthless. It is, therefore, necessary that the blades of a cutter of this 40 kind should be held in position with such firmness and strength as to effectually prevent any appreciable displacement thereof, and, inasmuch as the work of a milling cutter is upon metal, the strain to which 45 the blades are subjected is very great and to prevent this lateral displacement a fas-

tening device must have a large amount of strength. In providing means for fastening the blades in their seats I have formed in the head sockets 3 which are adjacent to and in the present instance extend substantially parallel with the blade seats and I have provided each blade with a part adapted to extend into the socket. Removably mounted in the socket is a fastening member which engages that portion of the blade which extends into the socket and holds the same firmly against movement. The fastening member and the socket preferably have interlocking devices which permit of said member being quickly and easily placed in position, and render the same very strong when so placed. In the present arrangement of mechanism I have shown each blade seat as communicating with its socket 3 by means of a radial slot 4 which is of a width sufficient to receive the projecting part of the blade and permit the blade to be placed in position. The projecting part of the blade may be of any suitable form but, to facilitate manufacture, I prefer that it should be made separate from the blade and attached thereto. To this end I have formed each blade with a curved recess 5 in its forward face and have inserted in this recess, preferably by driving, a metal block, such as a disk 6. The disk is inserted so tightly in its recess that it is firmly secured to and becomes a part of the blade. The diameter of the disk is such that it projects through the slot 4 into the socket 3 and its thickness is such that while it is capable of free radial movement in the slot, it is held against lateral movement therein, thus causing it to hold the blade against lateral displacement. To retain the blade in its seat I preferably employ a single fastening member which is here shown in the form of a screw 7 having a screw-threaded portion adapted to engage a screw-threaded extension 8 to the socket. The head of the screw has its under surface shaped to fit against the adjacent edge of the block or disk so that the fastening device when screwed into position will bear 100 tightly against the edge of this disk and will engage such portions of the same as will hold it securely against radial or edge-wise movement. The outer face of the head of the screw or fastening device preferably lies substantially flush with the adjacent portion of the periphery of the cutter head

and is provided with an opening to receive an implement to actuate the same, such as a slot 9 to receive the bit of a screw driver or an angular socket to receive a corresponding wrench, both types of screw being on the market.

The device will be fully understood from the foregoing description and it will be apparent not only that the device possesses great strength and is very positive in its action but that it contains a minimum number of parts, there being in fact but one part to the fastening device, that is, the screw, because the disk or projection 6 is preferably rigidly secured to and forms a part of the blade, although a satisfactory device could be made with the disk loose in its seat in the recess of the blade, so long as the fit between the blade and the disk is such as to prevent any material relative movement of these parts. Further, it will be apparent that it is not necessary to place the blade and fastening member in position simultaneously in order to cause a proper engagement of the parts. The blade may be placed in its seat and the fastening member screwed down afterward. Further, the fastening member itself directly engages that part of the blade which extends into the socket and the use of a thimble or interposed member to form the connection is rendered unnecessary, thus materially simplifying the construction and lessening the cost of manufacture, as well as facilitating the assembling of the parts.

Having thus fully described my invention, what I claim as new and desire to secure by Letters Patent, is:—

1. The combination, with a cutter head having a blade seat, and a socket adjacent to said seat, of a blade mounted in said seat and having a part extending into said socket, and a fastening device screw-threaded into said socket and having a head, that part of said blade which extends into said socket being arranged to be engaged by said head.

2. The combination, with a cutter having a blade seat, and a socket adjacent to said seat, of a blade mounted in said seat and having a part extending into said socket and held against lateral displacement, and a fas-

tening device mounted in said socket and having a head to engage said part of said blade and hold it against longitudinal movement.

55

3. The combination, with a cutter head having a blade seat, a socket adjacent to said seat, and a slot connecting said seat and said socket, of a blade mounted in said seat, a block secured to said blade and extending through said slot into said socket, and a fastening device mounted in said socket and having a part to engage said block to hold the same against movement in said slot, said fastening device and said socket having interlocking parts.

60

4. The combination, with a cutter head having a blade seat, a socket having a screw-threaded portion, and a slot connecting said socket and said seat, of a blade mounted in said seat, a part carried by said blade, extending through said slot into said socket, and a screw-threaded device mounted in said socket and having a head to engage said part carried by said blade.

75

5. The combination, with a cutter head having a blade seat, a socket having a screw-threaded portion, and a slot connecting said socket and said seat, of a blade mounted in said seat, a disk mounted edgewise in said slot, secured to said blade and projecting into said socket, and a screw-threaded fastening device mounted in said socket and having a part adapted to engage the edge of said disk to hold the same against movement in said slot.

80

6. The combination, with a cutter head having a blade seat, a socket having a screw-threaded portion, and a slot connecting said socket and said seat, of a blade mounted in said seat and having a recess in the face thereof, a disk mounted in said recess and extending through said slot into said socket, and a screw mounted in the screw-threaded portion of said socket and having its head arranged in engagement with said disk.

95

In testimony whereof, I affix my signature in presence of two witnesses.

JOHN F. MORGAL.
